UNITED STATES PATENT OFFICE

106,954

DESIGN FOR A NEGLIGEE

Ethel Eaton Stricker, New York, N. Y.

Application September 27, 1937, Serial No. 71,819

Term of patent 3½ years

To all whom it may concern:

Be it known that I, Ethel Eaton Stricker, a citizen of the United States of America, residing in New York city, in the Borough of Manhattan, county and State of New York, have invented a new, original, and ornamental Design for a Negligee, of which the following is a specification, reference being had to the accompanying drawing, forming part thereof, wherein,

Figure 1 is a front view of a negligee showing my new design.

Figure 2 is a rear view of the negligee shown in Figure 1.

The characteristic feature of my design resides in the specific arrangement of the embroidery on the neck and sleeves of the robe as shown.

I claim:

The ornamental design for a negligee, substantially as shown and described.

ETHEL EATON STRICKER.
